UNITED STATES PATENT OFFICE.

GEORGE ARTHUR TURNER, OF LEEDS, ENGLAND, ASSIGNOR TO H. & M. PATENTS LIMITED, OF LEEDS, ENGLAND, A COMPANY OF GREAT BRITAIN AND NORTHERN IRELAND.

MEANS OR APPARATUS FOR SUPPLYING LIQUID DISINFECTANTS TO THE WATER CONTAINED IN TANKS USED FOR WATER-CLOSETS AND OTHER LIKE FLUSHING PURPOSES.

Application filed May 12, 1928, Serial No. 277,279, and in Great Britain May 20, 1927.

This invention relates to improvements in means or apparatus for automatically regulating the flow of liquid disinfectants to the water contained in a tank or cistern or other 5 receptacle,—all of which are hereinafter termed and included in the term “the cistern”,—employed for water closet and other like flushing purposes.

The type of apparatus to which this invention is particularly applicable is that in which the receptacle in which the liquid disinfectant is placed is separate from, or arranged on or in the cistern. It is preferred to attach the receptacle to and above the cistern and to 15 provide means for an intermittent automatic supply of liquid disinfectant to the water in the cistern.

In carrying this invention into practice the disinfectant receptacle may be made in a 20 form in which the mechanism for operating and controlling the flow of disinfectant to the water in the cistern is arranged within the receptacle in which the liquid disinfectant is placed.

25 In the drawings hereunto annexed:—

Fig. 1 a front and sectional elevation of a form of apparatus in which the mechanism for operating and controlling the flow of the disinfectant is arranged within a compartment formed within the receptacle employed for containing the said liquid.

Fig. 2 a part sectional plan of Fig. 1 with a portion of the cover of the receptacle removed.

35 Fig. 3 a section on line A, B, Fig. 1.

Like parts in all the views are marked with similar reference numerals.

1 is the cistern which may be made of metal or of wood lined with sheet lead or any other 40 suitable material and it is made of the usual and ordinary shape and construction. As illustrated in the drawings the cistern 1 is shown with an open top, but when required it may be provided with a fixed or adjustable 45 cover.

3 is the receptacle for the liquid disinfectant, hereinafter termed “disinfectant”,—and it is made in one or more portions of any 50 suitable material that will not be injured by the chemical action of the disinfectant. A suitable material for the receptacle 3,—which

is made of any required size and shape,—is cast or formed of sheet or other metal pressed or formed to the required shape, or it may be formed of glazed earthenware.

55

At the bottom 7 of each end of the receptacle is provided a lug or flange 4 which projects in an outward direction and also is level with the bottom of the receptacle. The lugs or flanges 4, 4, provide means whereby the receptacle 3 is fixed, say, by screws 5, 5, to the upper surface of the cistern 1. The receptacle 3 is made rectangular with vertical sides 9, 9^x and ends 10, 10^x and it is provided with an open top which is closed by a fixed or detachable cover 11. The bottom 7 of the receptacle 3 is made level.

60

In the side 9^x of the disinfectant receptacle 3 is formed a vertical opening 12 which extends downwards from the open top 6 of the receptacle to or within a suitable distance of the bottom 7 thereof, and a vertical partition 13 is provided in the interior of the receptacle 3 which extends from the said top to the inner surface of the bottom 7 of the 75 receptacle. The vertical partition 13 extends a suitable distance from the end 10 of the receptacle to beyond the opening 12 as shown at Fig. 2. The vertical partition 13 is arranged parallel with the side 9^x of the receptacle 3. 80 The space 27 between the inner surface of the vertical partition 13 and the inner surface of the side 9^x of the receptacle 3 is closed by an end piece 14 which does not extend to the top of the vertical partition 13 and the top 85 of the receptacle 3 Figs. 2 and 3.

80

By making the end piece 14 shorter in depth than the vertical partition 13 a cavity 15,—Fig. 3,—is formed for the reception of a valve operating lever comprising two arms 90 16 and 17 arranged at or about right angles to each other. The top of the piece 14 acts as a stop for limiting the downward movement of the arm 16. The double armed lever is mounted upon a bolt 18,—having nuts 30, 95 31 on its ends,—which passes through the boss 19 of the said lever, and the outer and free end of the horizontal arm 16 is slotted or bifurcated, for permitting of the reduced and screw threaded end 20 of the vertical 100 valve rod 21 to pass through it. A nut or disc 21^x provided with a milled flange is em-

ployed for adjusting the position of the vertical valve rod 21. The lower end of the rod 21 is reduced in size or diameter for forming a valve 22 which is adapted to work 5 against the seating 23 formed in a flanged boss 25 formed on or fixed by a collar 25^x to the upper surface of the bottom 7 of the receptacle 3. A central hole 24 is arranged to pass through the boss 25 which is formed on 10 the surface of the bottom of the receptacle for the discharge of the disinfectant into the water within the cistern 1.

A block,—hereinafter termed "a cam piece 26",—is arranged to work in the space 27 15 between the inner surface of the side 9^x and vertical partition 13 and the cam piece is mounted on the pivot 28 and which is in the form of a spindle provided with screw threaded ends upon which are mounted respectively 20 the nuts 32, 33. The cam piece 26 has a V shaped recess 26^x formed in its periphery whereby a double cam is provided, one portion of which acts against the outer surface 25 of the pendant arm 17 and the other portion of the cam is acted upon by the inclined surface of the disc 29. The cam 26 is mounted loosely upon its pin or spindle 28 so as to enable it to act as a tripping device for intermittently acting upon the outer surface 30 of the arm 17, and the position of the V shaped opening 26^x is so arranged that one portion of the cam is heavier than the other for enabling it to act as the weight for returning the cam to its normal position.

To the bottom 7 of the receptacle 3 is fixed 35 a tubular pendant bearing 34,—Fig. 1,—which is of the same internal bore as the pipe 36 fixed within the float 35. The float 35 is cylindrical in form and closed at both of its 40 ends which are connected centrally together by the pipe 36. On the top of the float is fixed by soldering or other means a boss 37 provided with a central hole of the same diameter as the internal bore of the pipe 36 45 through which passes a vertical rod 38 in which the float is adjustably fixed by a set screw 39. The vertical rod 38 passes through the pipe 36 and also projects beyond the top of the float 35. To the upper end of the rod 50 55 is fixed the disc 29 against which the minor portion of the cam 26 acts. The disc 29 rises and falls in the space 27 of the receptacle 3 simultaneously with the rise and fall of the float 35 the movement of which is controlled by the rising and falling levels of the water in the cistern 1.

On the descent of the vertical rod 38 and the float 35 which is attached thereto as described,—during or after the discharge of 60 the flushing water has taken place,—the inclined periphery of the disc 29, acts upon the portion at the front of the cam 26 for raising the vertical rod 21 and lifting the valve portion 22 of the rod 21 clear of the valve seating 23 for allowing the required supply of dis-

infectant to pass through the discharge opening 24 to the water in the cistern 1.

During the movement of the cam 26 the periphery of its major portion will act upon the pendant arm 17 thereby raising the horizontal arm 16 which lifts the rod 21. Simultaneously the float permits of the rod 38 to descend with the flushing water in the receptacle 1. During the descent of the rod 38 and as soon as the inclined periphery of the disc 29 is clear of the front portion of the cam 26 its weighted portion and the levers 16 and 17 will return to their normal position for permitting of the vertical rod 21 and the valve 22 to descend upon its seating 23 for cutting off the supply of disinfectant to the water in the cistern 1. As soon as the water is again allowed to flow into the cistern 1 by means of the ordinary bell tap, the float 35 will commence to rise and by it being secured upon the rod 38, the float 35 and disc 29 will all be raised simultaneously. On the upper surface of the disc 29 coming in contact with the minor portion of the cam 26, the latter will be raised a sufficient height to permit of the disc 29 being raised into the position shown at Fig. 1. During the just described tripping motion of the cam 26 no movement of the rod 21 takes place until the inclined periphery of the disc 29 on its descent again 95 comes in contact with the minor portion of the cam 26, as previously described.

What I claim is:—

1. Apparatus for supplying disinfectants to water contained in a flushing cistern having in combination a receptacle for the disinfectant provided with a discharge opening communicating with the said cistern, a discharge valve for opening and closing the opening, said valve forming part of a vertical rod, means arranged within the receptacle for intermittently raising the valve rod, a cam mounted loosely upon a spindle, an independent float working within the cistern, a rod upon which the float is adjustably fixed having a disc secured to its upper end for intermittently actuating the cam for raising the discharge valve.

2. Apparatus for supplying disinfectants to water contained in a flushing cistern having in combination a receptacle for the reception of the disinfectant having an open top, a vertical opening formed in one of its sides, and an internal chamber in communication with the said vertical opening, a discharge opening formed in the bottom of the receptacle, a double-ended lever pivoted in the said chamber one of its arms projecting horizontally from the chamber over the end of the latter into the receptacle, the other arm hanging pendants in the chamber, a vertical rod adjustably connected at its upper end to the horizontal arm of the said lever, and having a valve formed on its lower and reduced end, for opening and closing the discharge open- 130

ing, a double and weighted cam mounted loosely upon a spindle fixed transversely within the said chamber, a float provided with closed ends and having a central vertical tube, a flushing cistern in which the float operates, a vertical rod upon which the float is adjustably mounted, said rod being of such a length that it passes through the bottom of the receptacle into the said chamber, a disc 10 mounted upon the upper end of the rod for intermittently acting upon the cam for tripping the double-ended lever for discharging the disinfectant into the cistern.

3. Apparatus for supplying disinfectants to water contained in a flushing cistern having in combination a flushing cistern having a cylindrical float working therein, said float having a central tube fixed therein, a detachable cover for the receptacle, a receptacle for 15 the disinfectant fixed on the top of the cistern, said receptacle being open at its top and having a chamber formed therein, one of the sides of the said receptacle having a

vertical opening formed therein which communicates with the internal chamber, and 25 tripping means comprising a weighted cam having a V-shaped opening formed in its periphery, a spindle fixed transversely in the said chamber upon which the cam is loosely mounted, a double-ended lever pivoted upon a spindle fixed transversely within the said chamber, one arm of the lever being arranged to pass over the end of the chamber into the receptacle, and the other arm hanging pendantly in the chamber against which the cam 30 acts, a vertical rod adjustably fixed by one of its ends to the float and having a disc secured to its upper end which actuates the cam, and a second vertical rod arranged in the receptacle, one end of the rod being adjustably attached to the horizontal arm, and having a valve formed on its lower end, the supply 35 of disinfectant being controlled by the movement of the float within the cistern as set forth.

GEORGE ARTHUR TURNER.
